INKING MECHANISM FOR PRINTING-PRESSES.

1,200,771.

Specification of Letters Patent.

Patented Oct. 10, 1916.

Application filed August 20, 1913. Serial No. 785,717.

To all whom it may concern:

Be it known that I, BYRON JOSEPH SLYTER, a citizen of the United States, residing at and whose post-office address is 22 Valley street, in the city and county of San Francisco, State of California, have invented a new and useful Improvement in Inking Mechanisms for Printing-Presses.

This invention relates more particularly to an attachment to the regular inking rollers, of a set of distribution rollers, in contact therewith and driven thereby.

Objects.—Among the many objects of this invention are: to provide means for distributing the ink on the form rollers evenly, to insure an even inking of the type surface in the form, over which the form rollers pass; to provide means for controlling the application of ink to the form to be printed, regardless of the quantity of ink desired, or its consistency or body.

The invention possesses other advantageous features, that with the foregoing will be set forth at length, in the following description, wherein I shall outline in full that form of the invention selected for illustration in the drawings, accompanying and forming part of the present specification.

30 The novelty of the invention will be included in the claims succeeding said description. From this it is apparent, that I do not restrict myself to the showing made by said drawings and description, as I may 35 adopt many variations within the scope of my invention, as expressed in said claims.

Drawings.—In the drawings: Figure 1— is a fragmentary perspective view of the inking mechanism of a conventional platen printing press, having this invention applied thereto. Fig. 2— is an end view of the inking rollers and the mountings of the same, illustrating the application of this invention as an attachment thereto. Fig. 3— 45 is a diagrammatic end view of the regular inking rollers, illustrating the relation thereto of the distribution rollers of this invention.

Construction.—The construction of this 50 invention as illustrated in the drawings,

includes the distribution rollers 1, 2 and 3. These rollers are preferably of the regular printing roller formula composition, tempered or modified to suit the particular class of work to which they are applied, and cast 55 about metallic cores or shafts 4, 5 and 6. These shafts are provided with the enlargements or collars 7, 8 and 9, and are journaled in the bearings provided in the end blocks 10—10.

The end blocks 10—10 will vary with the type of saddles in which the regular rollers 12, and 13 are journaled. These saddles usually comprise, as shown, a stem 14 with the transverse head 15, having the open bearings 16—16 within which the shafts 17 and 18 of the rollers are journaled. The ends of the heads 15, have the depending lugs 19—19 drilled to receive the transverse pin 20, inserted to prevent the accidental disengagement of the rollers from the heads 15.

The roller saddles are attached with interposed springs, to a swinging arm X geared to the driving mechanism of the press, the swing of this arm causes the attached rollers to ride over the surface of the ink disk 21, thence returning, and down over the surface of the form. The traction rollers 22 on both ends of the several shafts 17 and 18 of the ink rollers, travel on the 80 tracks 23—23 on each side of the bed of the press, rotating the ink rollers in their travel, and limiting their pressure against the form.

The ink is fed onto the ink disk from an ink fountain in a regulated flow, or otherwise introduced onto the disk. The rollers 12 and 13 travel across the face of the disk 21, which in turn is intermittently rotated by a ratchet or other mechanism geared to the driving mechanism of the press. 90 The ink is usually applied to the disk near the upper edge, as the disk is rotated past the fountain situated at the upper edge of the inclined disk. The up stroke of the swinging arm X carries the form rollers upward across the surface of the ink disk, from which they pick up the ink and distribute it onto the disk. This rolling action is depended upon to distribute the ink evenly, throughout the length of all the roll-

ers, and the surface of the disk. The return stroke of the swinging arm X, carries the form rollers downward across the disk and over the form, during the interval that 5 the platen swings back from the form. The above described inking action is more or less unsatisfactory, and confines this type of press to job work of small and limited surfaces, because of the unequal and uneven dis- 10 tribution of the ink over the form, due to the insufficient working or diffusion of the ink over the ink disk, and its transfer to the form rollers, in the short interval elapsing between strokes of the press. A third 15 inking form roller 24, is provided in an independent saddle, to facilitate rounding the corner 25 in the tracks 23, the function and operation of this roller is identical with the rollers 12 and 13.

20 This invention is applied in the following manner, and increases the efficiency of the regular inking mechanism, as will be herein-after described. The end blocks 10—10 as shown include the depending hook 26—26, giving to the internal contour of the end blocks the same outline as the saddles 11—11 over which they are slipped, and secured by the pins 20, extending through the hooks 26—26, and the lugs 19—19 of the saddles. 25

30 This assemblage makes the end blocks a combinative part of the saddles 11—11 in all their evolutions. The distribution roller 1, is located between the two form rollers 12 and 13 in tractive contact therewith. The 35 distribution rollers 2 and 3 are located above the form rollers 12 and 13 respectively, and in tractive contact therewith, substantially as shown. The ends of the shafts 4, 5 and 6 of the respective distribution 40 rollers are journaled in the end blocks as described, the collars 7, 8 and 9, preventing undue end play of these rollers, by abutment with the adjacent end blocks. By a mere duplication of parts, a distribution 45 roller or rollers could be applied to the single roller 24, but practice proves that this is not often required, except in very fine work where the ink must be regulated to a great nicety.

50 *Operation.*—The distribution rollers being in tractive contact with the form rollers, are rotated thereby in the reverse direction thereto, and being preferably considerably less in diameter, make several revolutions to one revolution of the form rollers. This difference in speed ratio, results in a quick and even dissipation of any excess of ink, accumulated at any point on the form roller, and its uniform distribution throughout the sur- 55 face of either or both of the form rollers, in contact with the distribution roller 1, and its further distribution on the respective rollers by their contacting distribution rollers.

60 65 It is obvious that the distribution rollers

picking up and holding the surplus ink from the form rollers, will feed this surplus during the period that the form rollers are traveling over the form and will give this surplus to the form rollers, as the form rollers give off their ink to the form, insuring a uniform inking of the form even though it contain, blocks, or plates of large area requiring much ink; insuring also that the proper functioning of the distribution rollers will prevent the deposit of an excess of ink at any point on the form.

75 By the use of this invention the maximum quantity of ink can be applied to the form without danger of blotting; very heavy viscous inks can be handled; or very thin tint can be applied evenly to tint blocks without danger of clouding, uneven or graduated distribution of ink on forms of large area.

80 85 In addition to the many technical advantages attending the use of this invention, it is simple, easily applied, and direct acting, requiring no extra skill in the operator to apply or operate it, and it requires no extra power or gearing to drive it. It broadens 90 the field of the platen press for the successful printing of tint blocks; labels; outlines and solid printings; both for large and small forms, in a manner and with results not heretofore attained, so far as I am aware, 95 except on cylinder presses.

Having thus fully described my invention, what I claim and desire to secure by Letters Patent is;

1. In a printing press, end saddles having 100 depending lugs; inking rollers journaled in said saddles; end blocks having depending hooks engaging said lugs; attaching pins passing through said lugs and said hooks; distribution rollers journaled in said blocks 105 in tractive contact with the said inking rollers.

2. In a printing press in combination, end saddles having depending lugs, inking rollers journaled in said saddles, end blocks having depending hooks engaging said lugs, attaching pins passing through said lugs and said hooks, and distribution rollers journaled in said blocks in tractive contact with said inking rollers, said distributing rollers 115 having axles provided with collars adapted to engage said blocks whereby the axial position of the distribution rollers is limited.

3. In a printing press in combination, end saddles, inking rollers journaled in said saddles, end blocks carried by said saddles, means for attaching said blocks to said saddles, and distribution rollers journaled in said blocks in tractive contact with the said inking rollers, said distribution rollers having axles provided with collars adapted to engage said blocks whereby the axial position of the distribution rollers is limited.

4. In a printing press in combination, end saddles having depending lugs, inking roll- 130

ers journaled in said saddles, end blocks having depending hooks engaging said lugs, inking rollers journaled in said saddles, distribution rollers journaled in said end blocks, one of said distribution rollers tractively engaging two inking rollers and the other distribution roller tractively engaging

one inking roller only, and attaching pin passing through said lugs and said hooks.

BYRON JOSEPH SLYTER.
